UNITED STATES PATENT OFFICE.

JOSEPH H. TEMPLIN, OF READING, PENNSYLVANIA, ASSIGNOR, BY MESNE ASSIGNMENTS, TO THOMAS V. ALLIS, OF NEW YORK, N. Y.

DIE FOR USE IN MAKING BARBED FENCING.

SPECIFICATION forming part of Letters Patent No. 450,045, dated April 7, 1891.

Application filed July 30, 1888. Serial No. 281,398. (No model.)

To all whom it may concern:

Be it known that I, JOSEPH H. TEMPLIN, a citizen of the United States, and a resident of Reading, in the county of Berks and State of Pennsylvania, have invented certain new and useful Improvements in a Combination of Dies for Use in Machinery for Making Barbed Strips, of which the following is a specification.

- 10 This invention consists of improved contrivances of dies for producing two barbed strips from a double blank strip by making slits at intervals along the strip in two parallel lines and a diagonal line connecting the parallel lines and making other slits in line with and opposite to the parallel lines of the first slits across the diagonal lines by which the blank strip is separated in two parts and pointed barbs are cut on the edge of each 20 part thus separated.

The invention comprises the combination of bending-dies with the improved slitting-dies for bending the barbs so cut for the required lateral projection from the strip, as 25 follows, referring to the drawings, in which—

Figure 1 represents face views of slitting-dies of my improved contrivances together with other slitting-dies and bending-dies used therewith. Fig. 2 represents a diagram of the 30 blank strip, showing the effect of the dies on it. Fig. 3 is a side elevation of the slitting and bending dies with a blank strip between them. Fig. 4 represents face views of the improved slitting-dies in a modified arrangement together with other slitting-dies and the bending-dies. Fig. 5 is a diagram of the strip, showing the effect of the dies of Fig. 4.

I provide two pairs of slitting-dies *a b*, both having cutting-edges partly in two parallel 40 lines *c* and partly in the intermediate diagonal line *d*, connecting the parallel lines, said lines being apart from each other the width of the barbs to be made, the diagonal lines of both pairs of dies being inclined in the same 45 direction, and the length of one pair of the dies being equal to the length of two barbs and two base-webs, by which the barbs remain joined to the strips, the other pair being the length of two barbs only and the two pairs 50 being located close together. The longer dies

are here represented as first in the order of arrangement, but they may be second. The effect will be substantially the same. These dies make two slits *a' b'* of like form in the blank strip *c'*, but differing in length, one in 55 advance of the other and their contiguous ends, respectively, in the different parallel lines of the cutting-edges and terminating in one and the same transverse line of the strip. The blank strip *c'* is fed along the length of 60 these two pairs of dies at each operation, so that the relations of the contiguous ends of the preceding slit *a'* and the successive slit *b'* are the same as those of the slits *a' b'*, that are made together—that is to say, the 65 slits are all uniformly the same as to their longitudinal order. Next following these slitting-dies are two pairs of parallel-edged slitting-dies *e f*, located apart from them the length of the retaining-webs *g* to be left on 70 barb-strip *h* and apart from each other the length of the similar retaining-web *g'* to be left on barb-strip *h'*. They cut the slits *i* each way from the diagonals of slits *a' b'* and complete the cutting of the barbs *j* and the 75 cutting of the barbed strips apart, the slits of one pair terminating in the uncut webs *g g'*, left at the ends of the short slit *b'*, and the slits of the other pair cutting through to the ends of the long slit *a'* alternately in the different parallel lines of slits *a'*, so that the 80 barbs are disposed in pairs on each barb-strip alternately. Next after the slitting-dies *e f* are bending-dies *k l* of suitable punch and matrix contrivance for bending the barbs laterally to the strip and arranged in two pairs 85 which bend the barbs alternately in opposite directions.

Both pairs of the slitting-dies *a b* may be made the length of the short pair in Fig. 1 90 and be located apart from each other the length of a connecting-web for the barbs, as represented in Fig. 4, provided web-cutters *n o* be employed for subsequently cutting apart the webs left at *p q* by such dies; but 95 this is a substantially equivalent device which I consider included in my invention.

What I claim, and desire to secure by Letters Patent, is—

1. The combination, with two pairs of slit-

ting-dies, as *a b*, having the cutting-edges partly in two parallel lines, as *c*, and partly in a diagonal line, as *d*, connecting said parallel lines, both diagonals being inclined in 5 the same direction, and the dies being arranged to make slits in line with each other, of two pairs of parallel-edged slitting-dies, as *e f*, arranged to make slits in extension of the parallel lines of the slits made by the first 10 dies across the diagonals thereof, respectively, substantially as described.

2. The combination, with two pairs of slitting-dies, as *a b*, having the cutting-edges partly in two parallel lines, as *c*, and partly 15 in a diagonal line, as *d*, connecting said parallel lines, both diagonals being inclined in the same direction, and the dies being arranged to make slits in line with each other, of the two pairs of parallel-edged slitting-dies, 20 as *e f*, arranged to make slits in extension of the parallel lines of the slits made by the first dies across the diagonals thereof, respectively, and bending-dies, as *k l*, arranged to bend the

barbs cut by said slitting-dies laterally to the strips, substantially as described. 25

3. The combination of two pairs of slitting-dies, as *a b*, having the cutting-edges partly in two parallel lines, as *c*, and partly in a diagonal line, as *d*, connecting said parallel lines, both diagonals being inclined in the same direction, one pair being the length of 30 two barbs and the other pair the length of two barbs, and two base-webs joining the barbs to the strips, and two pairs of parallel edged slitting-dies, as *e f*, arranged to make 35 slits in extension of the parallel lines of the slits made by the first dies across the diagonals thereof, respectively, substantially as described.

Signed at New York city, in the county and 40 State of New York, this 2d day of May, A. D. 1888.

JOSEPH H. TEMPLIN.
